EEG headset for emotion detection. Online, published date Jan. 9, 2018. Retrieved on Mar. 17, 2019 from <URL: <https://phys.org/news/2018-01-eeg-headset-emotion.html>>.*Primary Examiner — Susan Bennett Hattan*Assistant Examiner* — Omeed Agilee(74) *Attorney, Agent, or Firm* — Kirschstein, Israel,
Schiffmiller & Pieroni(57) **CLAIM**

The ornamental design for an electroencephalogram headset, as shown.

DESCRIPTION

FIG. 1 is an overhead, front and side, perspective view of an electroencephalogram headset according to our new design.

FIG. 2 is an overhead, front perspective view thereof.

FIG. 3 is a front, elevational view thereof.

FIG. 4 is a rear, elevational view thereof.

FIG. 5 is a left side, elevational view thereof.

FIG. 6 is a right side, elevational view thereof; and,

FIG. 7 is a top plan view thereof.
